WEB GUIDE MECHANISM

William C. Nash, Neenah, Wis., assignor of one-fifth to Mary Jones and one-fifth to Marie Duvall Nash, both of Neenah, Wis., and one-fifth to William M. Nash, Chicago, Ill., and one-fifth to Roy A. Nash, New Rochelle, N. Y.

Application February 27, 1936, Serial No. 66,079

2 Claims. (Cl. 74—241)

This invention relates to improvements in a web guiding device and refers specifically to a device for guiding an endless traveling web in substantially constant alignment while said web is traveling in a substantially vertical direction.

The object and advantages of my invention will be apparent from the accompanying drawings and following detailed description.

In the drawings, Fig. 1 is a diagrammatic side elevational view of a substantially vertically traveling web guided by my improved apparatus.

Fig. 2 is an enlarged elevational view of the guide roll actuating mechanism.

Fig. 3 is a sectional view taken on line 3—3 of Fig. 2.

Fig. 4 is a sectional view taken on line 4—4 of Fig. 2.

Fig. 5 is a sectional view taken on line 5—5 of Fig. 1.

Fig. 6 is a fragmentary detail elevational view illustrating particularly the means for limiting the guide roll actuating mechanism.

Referring in detail to the drawings, 1 indicates an endlessly traveling web which is adapted to pass over guide rolls, 2, 3, 4, 5 and 6.

In the paper making operation after the newly formed web has been stripped from the forming wire, the same is passed forwardly through one or more sets of presses and during passage through said presses the weak wet web is supported between two endlessly traveling felts or blankets. In Fig. 1 the web 1 comprises one of the traveling felts or blankets. Of course, it is essential that the felt or blanket be caused to travel in substantially constant alignment. Therefore, in view of the fact that the felt during its back travel is carried over a series of guide rolls positioned above or below the path of travel of the wet web, said felt must be caused to travel in substantially vertical directions.

My present invention is particularly applicable to the guiding of these traveling felts and although I do not wish to be limited to this application of my invention, the operation thereof will be described as being carried out in conjunction with the guiding of a felt.

The guide roll 5 is mounted upon shaft 7 and a sprocket wheel 8 may also be mounted upon said shaft. A sprocket chain 9 may travel around and be driven by the sprocket wheel 8, said chain in turn driving sprocket wheel 10 which is mounted upon shaft 11 journaled in the upper portion of standard 12 (Fig. 3). A standard 12 may be mounted upon the upper portion 55 of frame 13 and may be secured thereto by means

of bolts 14 or the like. A bevel gear 15 is mounted upon the end of shaft 11 and is adapted to mesh with a cooperating bevel gear 16 mounted upon shaft 17. Shaft 17 at its end may carry disc 18 and a pin 19 is eccentrically positioned upon the face of said disc. A connecting rod 20 is pivotally connected to pin 19 and is pivotally connected at its opposite end at 21 to the upper end of U-shaped member 22. A link 23 is also connected at the pivot point 21 and is pivotally anchored at its opposite end as at 24 to the frame 13. The U-shaped member 22 comprises spaced arms 25 and 26 which embrace or are disposed adjacent opposite faces of ratchet wheel 27. The ratchet wheel 27 is rigidly mounted upon shaft 15 5 which is journaled in bearings 28 and 30 carried by frame 13. The wheel 27 carries an integral hub 31 which abuts bearings 29 and 30 at its opposite ends whereby lateral motion or motion of the wheel 27, or motion along the 10 length of shaft 28 is prevented.

It can readily be seen that as web or blanket 1 travels over guide rolls 2, 3, 4, 5 and 6, the rotary motion of guide roll 5 will drive sprocket wheel 10 which, in turn, imparts motions to the disc 18 which reciprocates connecting rod 20. In view of the fact that the U-shaped member 22 is connected to the anchoring link 23, the reciprocation of connecting rod 20 imparts a substantially vertical motion to the U-shaped member 30 22. Strictly speaking, the motion of pivot point 21 is along an arc the radius of which is equal to the length of the anchoring link 23. However, due to the relative length of the link 23 with respect to the throw of the eccentric pin 19, the motion of the pivot point 21 is, for all practical purposes, substantially in a vertical line. It can readily be seen, therefore, that under normal operation the U-shaped member 22 oscillates upwardly and downwardly, the arms 25 being substantially equally spaced from the wheel 27.

A bracket 32 is mounted upon frame 13 and is secured thereto by means of bolts 33 or the like. The end of the bracket 32 carries a bar 34 which is provided with a slot 35 which traverses a substantial portion of the length of bar 34. A second bar 36 is adjustably secured to bar 34, the securing means comprising screw 37 which 50 can be rotated by means of hand wheel 38, screw 37 being adapted to project through the slot 35 and anchor bar 36 at a desired position along the length of slot 35. Bar 36 is also provided with a longitudinally extending slot 39. A screw 40 pro- 55

jects through slot 39 and is manipulated by hand wheel 41 to secure the member 42 to the bar 36 at a desired position along the length of the slot 39. The member 42 carries sleeve 43 which 5 serves as a bearing for pin 44. An arm 45 (Fig. 1) is secured at one of its ends to the pin 44, said arm terminating at its opposite end in two spaced bifurcated projections 46. A feeler or palm 47 carries spaced lugs 48 upon its rear 10 surface, said lugs being secured to the bifurcated arms 46 by means of pin 49. A coil spring 50 embraces pin 49 between the bifurcated arms 46 for a purpose to be hereinafter more fully described.

15 In utilizing my invention the bars 34 and 36 and the member 42 are so positioned as to bring the face of palm 47 adjacent the desired path of travel of the edge of the web or felt 1.

An arm 51 is carried at the opposite end of 20 pin 44 and the extending end of said arm is pivotally connected to link 52. The opposite end of link 52 is, in turn, pivotally connected to the extending end of an arm 53, said arm being keyed to shaft 54, which in turn is supported by the 25 extension 55 formed integral with the end of bar 34. A coil spring (not shown) circumscribes shaft 54 and normally urges palm 47 toward the edge of the web 1. Shaft 54 carries at its opposite end arm 56 which, in turn, is pivotally connected to the member 26 comprising one of the U-shaped elements 22.

As has been hereinbefore described, when the web or felt 1 is caused to travel, roll 5 is rotated and as a consequence sprocket chain 9 is driven 35 which, in turn, drives sprocket wheel 10. When sprocket wheel 10 is so driven, the disc 18 is rotated and reciprocating motion is imparted to the U-shaped member 22. During normal operation of my device, that is, when the web or 40 felt 1 is traveling in desired, constant alignment, the U-shaped member 22 merely reciprocates vertically, both arms 25 and 26 being out of contact with the wheel 27 and being substantially equally spaced from the respective opposite 45 faces of said wheel. Pawls 58 and 59 are adjustably carried at the ends of respectively, arms 25 and 26. Each face of the wheel 27 is provided with ratchet teeth 60 and 61, said teeth being formed adjacent the periphery of the 50 wheel and being pitched in opposite directions.

It can readily be seen that during operation of my device lateral shifting or creepage of the web or felt 1 will cause palm 47 to move which, in turn, rotates pin 44. By means of the arm and 55 linkage mechanism connecting pin 44 and the U-shaped member 22, said member will be rocked to bring either pawl 58 or pawl 59 into contact with teeth 60 or 61, depending upon the direction of the shift of the web or felt 1. Of course, 60 simultaneously with the shifting of the member 22, said member is also reciprocated vertically and, consequently, either pawl 58 or pawl 59 will engage the ratchet teeth 60 or 61 as the case may be, and move wheel 27 upwardly to 65 downwardly as viewed in Fig. 2.

The spring upon shaft 54 tends to keep palm 47 in contact with the edge of the web 1 if said web tends to move away from said palm. If the web moves toward the palm at a greater rate 70 than the web shifting mechanism can operate, spring 50 permits palm 47 to flex and therefore prevents injury to the web or palm.

Shaft 28 upon which ratchet wheel 27 is mounted carries at its end sprocket wheel 62 75 which upon being rotated by movement of wheel

27 drives sprocket chain 63. Sprocket chain 63 is trained around sprocket wheel 64 which, in turn, is mounted upon shaft 65 (Fig. 5). Shaft 65 is journaled in a wall of housing 66 which may be mounted upon any suitable support (not 5 shown). A substantially vertically positioned screw 67 may also be journaled in the upper and lower portions of the housing 66, the upper end of said screw comprising an open-top bearing 68 in which shaft 69 is journaled, said shaft 10 carrying guide roll 6. A bevel gear 70 is keyed to shaft 65 within housing 66 and meshes with a cooperating bevel gear 71 which is threadedly mounted upon screw 67. The arrangement is such that upon rotation of sprocket wheel 64, 15 bevel gear 71 is rotated and being threadedly engaged with screw 67, said screw is moved upwardly or downwardly. It can readily be seen therefore that one end of roll 6 is therefore moved upwardly or downwardly. Hence, when 20 web or felt 1 creeps laterally from a predetermined aligned position, palm 47 actuates mechanism which causes one end of roll 6 to be moved upwardly or downwardly. The shaft 67 at the opposite end of roll 6 is pivoted in a swivel bearing (not shown) whereby roll 6 may be canted from its normal horizontal position by upward or downward movement of screw 67. This action of roll 6 tends to shift the web or felt 1 back to its proper position of alignment.

30 A spur gear 72 is also mounted upon shaft 28 and is rotated when wheel 27 is moved by either pawl 58 or 59 and, consequently, spur gear 72 and sprocket wheel 62 also mounted upon shaft 28 move in unison. Therefore, whenever the end 35 of roll 6 is moved upwardly or downwardly to return web or felt 1 to desired position, spur gear 72 is rotated. Spur gear 72 meshes with a cooperating larger spur gear 73 mounted upon shaft 74 which, in turn, is journaled in bearing 40 75 carried by frame 13. A worm pinion 76 is also mounted upon shaft 74 and engages with worm wheel 77 which is mounted upon one end of shaft 78. At the opposite end of shaft 78 a disc 79 is positioned which is provided with a 45 circumferentially arranged series of apertures 80. A screw 81 is positioned in one of the apertures 80, all of which are internally threaded so that they may receive the screw 81. An arm 62 is pivotally connected to arm 26 of the U-shaped 50 member 22, the opposite end of said arm being provided with a slot 83. The end of arm 82 having slot 83 is provided with a series of spaced apertures 84 through which cotter-pins 85 may be positioned. Arm 82 normally extends substantially horizontally from arm 26 and screw 81 may be positioned through slot 83.

When the web or felt 1 shifts thereby causing ratchet wheel 27 to be rotated and in turn causing gear 72 to be rotated, said gear drives spur gear 73, worm pinion 76, worm wheel 77, shaft 78 and disc 79. Consequently screw 81 is moved within slot 83. To prevent abnormal shifting or raising or lowering of roll 6, cotter pins 85 may be positioned through appropriate apertures 84 65 so as to limit the movement of screw 81 within slot 83. It can readily be seen that if disc 79 is rotated to too great an extent, pin 81 contacts one of the cotter pins 85 and prevents motion of the U-shaped member in one direction or the other. The gearing arrangement is such that if the mechanism tends to move roll 6 by engagement of pawl 58 with ratchet teeth 60 and this movement becomes excessive, disc 79 will rotate 70 in a clockwise direction, as viewed in Fig. 2, and 75

screw 81 will contact one of the cotter pins, namely the one to the left of the screw, thereby moving the U-shaped member 22 and causing disengagement of pawl 58 from teeth 60. If 5 the roll 6 is moved excessively in the opposite direction, that is, when pawl 59 repeatedly engages teeth 61, disc 79 will rotate in a counter-clockwise direction until screw 81 contacts cotter pin 85 and causes disengagement of pawl 59 10 from teeth 61 by rocking the U-shaped member in a counter-clockwise direction. By the provision of the coil spring 50 the operation of disc 79 which prevents excessive or extremely prolonged engagement of either pawl 58 or 59 with 15 the respective ratchet teeth 60 or 61, palm 47 is prevented from injuring the web or felt 1 since said spring will flex before injury to the web or to the mechanism results.

In the event that the web or felt 1 is to be 20 cleaned or for any other reason it is desired to render the device herein described inoperative, that is, to prevent upward or downward movement of the end of roll 6, a hairpin-shaped member 86 may be inserted in apertures 84 in arm 25 82 adjacent each side of screw 81. It can readily be seen that inasmuch as the disc 79 is positively connected and responsive to movement of the ratchet wheel 27, the U-shaped member 22 cannot be maintained in rocked position for any 30 substantial period of time. In other words, placing ratchet wheel 27 into operation causes the U-shaped member 22 to disengage from ratchet wheel 27 and render the latter inoperative.

I claim as my invention:

35 1. A device for guiding a moving web which

comprises in combination, a guide roll having its surface in contact with said web, a bearing for supporting one end of said guide roll, means for moving said bearing, means for driving said bearing moving means, a contact member movable in response to lateral movement of said web and an engaging member for connecting said driving means to a source of mechanical power, a connection between said contact member and said engaging member for connecting said driving means to said source of mechanical power in response to movement of said contact member, means synchronized with said driving means, and means connecting said synchronized means and said engaging member for limiting movement of said engaging member. 5 10 15

2. A device for guiding a substantially vertical moving web which comprises in combination, a guide roll having its surface in contact with said web, a bearing for supporting one end 20 of said guide roll, means for moving said bearing in a substantially vertical direction, means for driving said bearing moving means, a contact member movable in response to lateral movement of said web and an engaging member for 25 connecting said driving means to a source of mechanical power, a connection between said contact member and said engaging member for connecting said driving means to said source of mechanical power in response to movement of 30 said contact member, means synchronized with said driving means, and means connecting said synchronized means and said engaging member for limiting movement of said engaging member.

WILLIAM C. NASH. 35
